CLAIM

The ornamental design for a scarf for women, as shown and described.

DESCRIPTION

FIG. 1 is a perspective view of a scarf for women showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the area identified as '8' in FIG. 1.

The image in the middle of the scarf is decorative graphic on the surface.

The broken lines along the periphery of the scarf depict stitching lines and form part of the claimed design.

1 Claim, 8 Drawing Sheets
